Peter R. Kramer(57) **CLAIM**

The ornamental design for a wiring raceway, as shown and described.

DESCRIPTION

FIG. 1 is a front view.

FIG. 2 is a rear view.

FIG. 3 is view from right side.

FIG. 4 is a view from left side.

FIG. 5 is a top view.

FIG. 6 is a bottom view; and,

FIG. 7 is an elevational perspective view from rear-left angle.

The instant invention relates to the ornamental aspects of a wiring raceway.
